UNITED STATES PATENT OFFICE.

JESSE W. RENO, OF NEW YORK, N. Y., ASSIGNOR TO OTIS ELEVATOR COMPANY, OF JERSEY CITY, NEW JERSEY, A CORPORATION OF NEW JERSEY.

CONVEYER.

1,112,836.

Specification of Letters Patent.

Patented Oct. 6, 1914.

Application filed April 28, 1913. Serial No. 763,953.

To all whom it may concern:

Be it known that I, JESSE W. RENO, a citizen of the United States, residing in New York, in the county of New York and State 5 of New York, have invented a new and useful Improvement in Conveyers, of which the following is a specification.

My invention relates to a comb shaped landing for inclined elevators and is an improvement on the device shown and described in my Patent, No. 963,176, issued July 5, 1910.

One of the objects of my invention is to provide a comb shaped landing at the upper and lower ends of the inclined elevator, whereby the passengers in ascending or descending will be safely and comfortably received on and discharged therefrom.

Another object of the invention is to provide means which will effect the prompt release of wearing apparel of the passengers or any obstructions which might be drawn in at the landings.

The invention is more particularly applicable to that class of inclined elevators wherein the tread or surface upon which the passenger stands, is formed of longitudinal ridges and grooves, such as is shown in the patent referred to, and in this type of machine, it has occasionally been found that foreign substances, such as wooden chips or fragments of sole leather become wedged at the bottom of the grooves between the ridges of the machine, causing undue strain 30 on the prongs of the comb landing as is now commonly used, and which are usually made of cast iron, with the result that as the substance comes under the prong, the clearance between the prong and the bottom of the 35 groove is not sufficient to allow the substance to pass through thereby causing the breaking thereof. A broken prong is not only expensive, and troublesome to repair, but it may lead to a serious accident or injury to a 40 passenger before it is discovered, and to this end I provide a simple and efficient means which I will now describe.

Referring to the drawings, Figure 1 shows a side view partially in section, of an upper 50 and lower landing and a portion of an inclined elevator, with my invention applied thereto; Fig. 2 is a plan view of Fig. 1; and Fig. 3 is an enlarged elevational view of a

comb landing constructed in accordance with my invention.

In the following description, general reference will be made only, to the construction, etc., of the inclined elevator, as the same is clearly shown and described in the patent heretofore referred to.

The inclined elevator comprises a series of steps 1, which are hinged together in the form of an endless belt. The steps are provided with rollers 2 adapted to travel on track rails 3, which are suitably secured to a supporting structure 4. Each alternate step is provided with a section of rack 5, centrally secured to its under side, and the steps alternating with these are provided with a pair of racks 6. The ends of the double 65 racks 6 overlap the ends of the single racks 5, and these ends are provided with a pin connection 7, by means of which the steps are pivotally connected to each other.

A series of grooves 8 is formed in a tread 75 surface 9 of the steps, in alignment with each other and parallel to the longitudinal direction of the belt, and these grooves register with prongs 10 of comb landings 11, located at the upper and lower ends of travel 12 80 and 13 respectively.

The landing 11 comprises a plate 12', which forms the floor line at the upper and lower landings, and is held in position by means of screws 18. The floor plate is provided with bosses 14, through which a rod 15 extends, pivotally to support a plurality of prongs 10. The prongs are maintained in their normal horizontal position by gravity, and their inner ends rest upon the bottom 85 of the floor plate at a point 15'. Extensions 16 and bosses 17 on the bottom of the floor plate maintain the prongs in proper juxtaposition to each other.

The floor plate is positioned at the landings with respect to the inclined elevator, so that the prongs register with the grooves and extend therein a considerable distance, whereby the foot of the passenger can be slid upon the upper surface of the prongs 100 and the landing thus effected without any sudden jar or uncomfortable sensation to the passenger, and if by accident any part of the wearing apparel of a passenger, as for example, the train of a woman's dress, 105 should extend into the grooves and be drawn

in at the landing, the prongs being pivoted will effect a prompt release of the same without danger of injury to the passenger. Furthermore, if any obstructions such as 5 wooden chips, etc., should become wedged in the groove, between the treads and should pass under the prong, it will merely raise the latter into the position shown in dotted lines, Fig. 3, and as soon as the obstruction 10 has passed, the prong drops back into its normal position. The breaking of the prong is thus prevented, and the machine is much safer to operate than with my previous construction.

15 Having thus described my invention, what I claim and desire to protect by Letters Patent of the United States is:—

1. An inclined elevator having longitudinal grooves formed in its tread surface, and 20 a landing therefor provided with independently movable pivoted prongs which register with the said grooves.

2. An inclined elevator having longitudinal grooves formed in its tread surface, a 25 comb landing therefor having a plurality of independently movable pivoted prongs which register with the said grooves.

3. In an inclined elevator, the combination 30 with a series of treads operatively connected together in the form of an endless belt, having longitudinal grooves formed in its tread surface, a landing therefor having a plurality of independently movable pivoted prongs which register with the said 35 grooves.

4. In combination, an inclined elevator having longitudinal grooves formed in its tread surface, a comb landing therefor, comprising a floor plate, a plurality of pivoted 40 prongs which register with the said grooves, and means associated with the floor plate pivotally to support the said prongs.

5. An inclined elevator having longitudinal 45 grooves formed in its tread surface, and a landing therefor comprising a floor plate, prongs pivotally supported thereon and positioned to register with and extend into the said grooves.

6. An inclined elevator having longitudinal 50 grooves formed in its tread surface, and a floor plate therefor having pivoted prongs which register with the said grooves, the said prongs each having an abutment there-

on to maintain the prongs in a lateral position with the floor plate against the action 55 of gravity.

7. A comb landing for inclined elevators, comprising a floor plate having a plurality of prongs pivotally supported thereby.

8. A comb landing for inclined elevators, 60 comprising a floor plate, and a plurality of prongs pivotally supported thereby and extending laterally therefrom.

9. A comb landing for inclined elevators, comprising a floor plate having a plurality 65 of pivoted prongs, the said prongs each having an abutment thereon to engage the bottom of the floor plate, to maintain the prongs in a lateral position with the floor plate against the action of gravity. 70

10. A comb landing for inclined elevators, comprising a floor plate, a plurality of pivoted prongs extending laterally therefrom, and a rod associated with the floor plate pivotally to support the said prongs. 75

11. A comb landing for inclined elevators, comprising a floor plate having a plurality of pivoted prongs, the said prongs each having an abutment thereon to engage the bottom of the floor plate, and a rod associated 80 with the floor plate pivotally to support the said prongs.

12. A comb landing for inclined elevators, comprising a floor plate, a plurality of pivoted prongs extending laterally therefrom, 85 a rod associated with the floor plate for pivotally supporting the said prongs, and bosses integral with the floor plate for keeping the prongs in proper juxtaposition to each other.

13. A comb landing for inclined elevators, comprising a floor plate having extensions thereon which form bosses to receive a rod, prongs positioned between the bosses and pivotally supported on the said rods, the said prongs each having an abutment thereon engaging the bottom of the floor plate, to maintain the prongs in a lateral position with the floor plate against the action of gravity. 95

In testimony whereof, I have signed my 100 name to this specification in the presence of two subscribing witnesses.

JESSE W. RENO.
